(57) **CLAIM**

We claim the ornamental design for an augmented reality headset, as shown and described.

DESCRIPTION

FIG. 1 is a top perspective view of an augmented reality headset showing our new design in a use configuration; FIG. 2 is a bottom perspective view of the augmented reality headset in a use configuration illustrated in FIG. 1; FIG. 3 is a front perspective view of the augmented reality headset in a use configuration illustrated in FIG. 1; FIG. 4 is a right side elevation view of the augmented reality headset in a use configuration illustrated in FIG. 1; FIG. 5 is a left side elevation view of the augmented reality headset in a use configuration illustrated in FIG. 1; FIG. 6 is a front side elevation view of the augmented reality headset in a use configuration illustrated in FIG. 1; FIG. 7 is a back side elevation view of the augmented reality headset in a use configuration illustrated in FIG. 1; FIG. 8 is a top side elevation view of the augmented reality headset in a use configuration illustrated in FIG. 1; and, FIG. 9 is a bottom side elevation view of the augmented reality headset in a use configuration illustrated in FIG. 1. The broken lines are included for the purpose of illustrating environmental subject matter and form no part of the claimed design.
